FLUID COMPRESSING APPARATUS

Original Filed Aug. 16, 1919

UNITED STATES PATENT OFFICE.

ROBERT SUCZEK, OF PHILADELPHIA, PENNSYLVANIA, ASSIGNOR TO C. H. WHEELER MANUFACTURING COMPANY, OF PHILADELPHIA, PENNSYLVANIA, A CORPORATION OF PENNSYLVANIA.

FLUID-COMPRESSING APPARATUS.

Application filed August 16, 1919, Serial No. 317,875. Renewed May 9, 1923.

To all whom it may concern:

Be it known that I, ROBERT SUCZEK, a citizen of the Czecho-Slovak Republic, residing in the city and county of Philadelphia, State of Pennsylvania, have invented certain new and useful Improvements in Fluid-Compressing Apparatus, of which the following is a specification.

My invention relates to apparatus for compressing fluid, such as air, gas, vapor, or a mixture of any of them, by ejector action, that is, by the action of motive fluid, such as steam or other elastic fluid under pressure, which is allowed to expand and entrain the fluid to be compressed, the mixture of fluids travelling at high velocity losing its kinetic energy and increasing in pressure.

My invention relates more particularly to apparatus for compressing fluid in a plurality of stages by action thereon of motive fluid in one stage, the condensable fluid from that stage being condensed, the condensate removed, and the compressed fluid, as air, being acted upon in a later stage by any suitable pump, as a second ejector, further to raise its pressure.

In accordance with my invention an ejector delivers into the condenser in which there are provided means for ensuring satisfactory and substantially complete separation of condensate from the fluid, as air, undergoing compression. A further feature of my invention is a structure of the condensing structure in relation with the ejector wherein the mixture discharged from the ejector is passed through a plurality of tubes or passages, extending vertically or substantially so, the condenser having a plurality of passes, permitting the apparatus to take a larger diameter or shorter vertical length or height.

A further feature of my invention is the withdrawal of condensate from the end of each pass or group of condenser tubes.

A further feature of my invention resides in an arrangement whereby condensate at the upper end of a pass or group of condenser tubes is prevented from passing downwardly through the tubes conducting the air or other fluid which has undergone compression; and a further feature resides in the application of drain pipes as hereinafter described and

in the structure of such drain pipes and the mode of association with the condenser structure as a whole.

For an illustration of one of the various forms my invention may take, reference is to be had to the accompanying drawing, in which:

Fig. 1 is a vertical sectional view, partly in elevation, through structure embodying my invention.

Fig. 2 is a fragmentary vertical sectional view, on enlarged scale, of drain pipe structure.

Referring to the drawing, E is an ejector of any suitable type or structure, and in the example here illustrated is a tubular ejector comprising the motive fluid expanding nozzles N, the tubular converging diverging diffuser D, and the suction chamber A having the suction port A¹ through which enters the air or other fluid to be compressed, as for example, from a steam condenser or from any other chamber or region from which the air or other compressible fluid is to be withdrawn. Steam or other suitable motive fluid is supplied to the nozzles N through the pipe a controlled by valve b and delivering into the chamber c with which the nozzles N communicate. The ejector E is mounted upon box or chest B which is divided by the walls or partitions d and e into the three chambers f, g and h. These chambers have a wall formed by the tube sheet or plate i held between the box B and one end of the condenser shell C. Within the shell C are the downwardly extending plates or baffles j and k and the upwardly extending plate or baffle l, these plates or baffles dividing the interior of the condenser shell C into four passes in which are disposed four groups of tubes m, of brass or other suitable material secured by ferrules n in the tube sheet i and the lower tube sheet o held between the condenser shell C and the lower chest or box B¹. The condenser structure is supported upon legs L, L, extending downwardly from box B¹. By pipe threaded into the condenser shell C at p is delivered cooling fluid, as water, flowing downwardly to the left of the plate or baffle j, under its lower edge, then upwardly around the next group of tubes over the upper edge of the plate or

baffle l , then downwardly between the next group of tubes under the lower edge of the baffle or plate k and thence upwardly through the next group of tubes and out 5 through a pipe connecting to the condenser shell at q . With each of the second, third and fourth groups of tubes is associated one or more drain pipes r whose upper ends are substantially flush with the upper surface of 10 the tube sheet i and whose lower ends extend through openings in the lower tube sheet o , and surrounded by packing s , Fig. 2, held compressed by the long ferrule tube t threaded into the sheet o and having threaded on to 15 its lower end the trap or seal cap u extending upwardly and spaced from the exterior of the ferrule t , which latter has a plurality of openings v communicating with the space between the cap u and the exterior of the 20 tube t .

The ferrules employed in connection with the upper ends of the condenser tubes of the second, third and fourth groups are, as indicated in Fig. 1, at w , of substantial length, 25 thereby extending a substantial distance above the upper surface of the tube sheet i to prevent any water or condensate accumulating from entering the condenser tubes m .

In the lower chest or box B^1 is the dividing 30 partition or diaphragm x preventing equalization of pressure or other conditions as between the lower ends of the tubes of the first two groups and the lower ends of the tubes of the third and fourth groups. 35 Communicating with the two chambers in the chest B^1 are the pipes y and z , controlled, respectively, by the valves a^1 and b^1 and delivering into any suitable pipe or draw off c^1 to deliver the condensate to any 40 suitable device or region, as for example, delivering the condensate into the steam or condensate space of the steam condenser with which the ejector apparatus may be associated for withdrawing air or uncondensable gases or fluids therefrom. 45

In order that the chambers in the box or chest B^1 on opposite sides of the partition x shall remain sealed from each other, the pipe c^1 with which the pipes y and z communicate rises to any suitable level, as c^2 , 50 whereby there is formed a U tube structure in which water is retained to such level as to rise somewhat above the lower ends or outlets of the pipes y and z , that is, to height somewhat above the level c^3 , so that a mass 55 of water is continuously maintained in the pipes y and z sealing them against each other and thereby preventing communication through pipes y and z between the two chambers on opposite sides of the partition x in box or chest B^1 .

The chamber h in the chest B communicates through the conduit d^1 and the divided 60 passages e^1 with the suction of the radial flow ejector E^1 , comprising the nozzle struc-

ture N^1 , producing a disk-shaped jet, and the surrounding annular diffuser structure D^1 delivering into the discharge passage f^1 having the discharge outlet g^1 . The ejector E^1 may be wholly or partially supported 70 by the condenser structure through its connection therewith. Steam is delivered to the nozzle structure N^1 through the passage h^1 communicating with the steam delivery pipe i^1 , with which communicates also the 75 aforesaid steam pipe a .

The operation is as follows:

The air or other fluid to be compressed enters at A^1 into the suction chamber A of the ejector E , where it is acted upon in known manner by the steam issuing in jets from the nozzles N and delivered at high speed into the diffuser D where kinetic energy is converted into pressure, the mixture of motive fluid and steam and the air arriving in the chamber f at a pressure higher than that of the air entering at A^1 . The mixture passes downwardly through the condenser tubes m around which is flowing the cooling water, causing condensation 80 of the steam, the condensate or water together with the partially compressed air flowing downwardly through the pipes m into one of the chambers in the chest or box B^1 , the condensate remaining in such chamber and passing off through the pipe z while the air continues its passage upwardly through the condenser tubes m of the second group, where it is further cooled and more steam or motive fluid condensed, the air passing on upwardly into the chamber g while the condensate drips downwardly 85 through the pipes m into the aforesaid chamber in the box or chest B^1 , passing off through the pipe z , as described. The air and remaining steam then descend through the tubes m of the third group from the chamber g into the left hand chamber in the box or chest B^1 , the condensate then 90 passing off through the pipe y . Finally the air ascends again through the fourth group of tubes m , any remaining motive fluid or condensable vapor being condensed and running downwardly through the tubes m of the fourth group into the chamber of the box B^1 , and passing off through the aforesaid pipe y . The air arriving in the chamber h is free or substantially free of motive 95 fluid or moisture or vapor and passes to the suction chamber of the second stage ejector E^1 , where by the action of the steam from the nozzle N^1 it is further compressed in the annular diffuser structure D^1 and delivered at higher pressure into the discharge casing f^1 and thence through the outlet g^1 to atmosphere or into a chamber or region 100 at any other suitable pressure.

While an ejector E^1 is shown in the second stage, it will be understood that my invention is not limited to the use of an ejec-

85

130

- or, but in lieu thereof any other type of fluid compressing apparatus may be employed. It will further be understood that my invention is not limited to further compression of the air after passage through the condenser structure, that is to say, the second stage pump or ejector may be omitted, if circumstances require or render it desirable.
- 10 Any water collecting on the upper surface of the tube sheet i in chambers g and e runs off through the drain pipes r , and does not flow downwardly through the condenser tubes m communicating with these compartments g and h .
- 15 The water in flowing downwardly through a drain pipe r passes into its ferrule t , Fig. 2, through the opening v into the annular space between the cap or seal member u , and the exterior of the tube t rises in such annular space, overflows the upper edge of the member u into the compartment in the box B^1 , and is then carried off by pipe y or z . By thus having water or condensate standing in the trap or seal u , the upper and lower compartments with which the particular drain pipe r communicates are maintained isolated from each other as to their pressure conditions.
- 20 In case substantial quantities of water or condensate should gather in the chambers g and h , it is prevented from running down the pipes m by the high ferrules w serving in effect as dams at the entrances of the
- 25 tubes m .
- What I claim is:
1. Combined ejector-condenser structure comprising an ejector, a condenser into which said ejector discharges the mixture of motive fluid and fluid to be compressed, said condenser comprising a plurality of substantially vertically extending serially connected conduits into which said ejector discharges, said conduits forming a plurality of passes, and means for circulating cooling fluid around said conduits.
  2. Combined ejector-condenser structure comprising an ejector, a condenser into which said ejector discharges the mixture of motive fluid and the fluid to be compressed, said condenser comprising a plurality of groups of substantially vertically extending tubes serially traversed by discharge from said ejector and constituting different passes, and means for circulating cooling fluid around said tubes.
  3. Combined ejector-condenser structure comprising an ejector, a condenser into which said ejector discharges the mixture of motive fluid and fluid to be compressed, said condenser comprising separated tube sheets, a box forming a plurality of compartments with one of said tube sheets as a wall thereof, a group of tubes extending through said tube sheets from one of said compartments, a second group of tubes serially related to said first group of tubes and delivering into a second of said compartments, and dams at the upper ends of the tubes of said second group preventing entry of condensate into said tubes.
  4. Combined ejector-condenser structure comprising an ejector, a condenser into which said ejector discharges the mixture of motive fluid and fluid to be compressed, said condenser comprising separated tube sheets, a box forming a plurality of compartments with one of said tube sheets as a wall thereof, a group of tubes extending through said tube sheets from one of said compartments, a second group of tubes serially related to said first group of tubes and delivering into a second of said compartments, means for draining condensate from said second compartment to a space below the lower tube sheet, and dams at the upper ends of the tubes of said second group preventing entry of condensate into said tubes.
  5. Combined ejector-condenser structure comprising an ejector, a condenser into which said ejector discharges the mixture of motive fluid and fluid to be compressed, said condenser comprising separated tube sheets, a box forming a plurality of compartments with one of said tube sheets as a wall thereof, a group of tubes extending through said tube sheets from one of said compartments, a second group of tubes serially related to said first group of tubes and delivering into a second of said compartments, means for draining condensate from said second compartment to a space below the lower tube sheet, said condensate draining means comprising a tube terminating substantially flush with the upper face of the upper tube sheet and terminating at its lower end below the lower tube sheet in a liquid seal device.
  6. Combined ejector-condenser structure comprising an ejector, a condenser into which said ejector discharges comprising tube sheets disposed one above the other, condenser tubes terminating in said tube sheets, and long dam-forming ferrules connecting said tubes at their upper end to the upper tube sheet.
  7. Combined ejector-condenser structure comprising an ejector, a condenser into which said ejector discharges comprising tube sheets disposed one above the other, groups of condenser tubes terminating in said tube sheets and serially related with respect to the discharge from said ejector, and drainage means for each group of tubes comprising a tube receiving condensate at its upper end, and a cup-shaped structure at the lower end of said tube adapted to hold liquid for sealing the space surrounding the lower end of said tube with respect to the interior of said tube.

8. Combined ejector and condenser structure, an ejector, condenser structure into which it discharges comprising vertically disposed tubes through which the ejector 5 discharge passes, a tube sheet in which said tubes terminate, a chest or box having a plurality of chambers receiving condensate from said tubes, independent pipes leading from said chambers, and means for preventing communication of said chambers with each other through said pipes.

9. Combined ejector and condenser structure, an ejector, condenser structure into which it discharges comprising vertically 15 disposed tubes through which the ejector discharge passes, a tube sheet in which said tubes terminate, a chest or box having a plurality of chambers receiving condensate from said tubes, independent 20 pipes leading from said chambers, and a pipe into which said pipes deliver, said pipe ascending to a height causing condensate continuously to stand in said pipes to prevent communication therethrough between 25 said chambers.

10. Multi-stage ejector-condenser structure comprising serially connected ejectors, an interstage condenser into which one of said ejectors discharges the mixture of motive fluid and fluid to be compressed, said condenser comprising a plurality of groups of vertical conduits, chambers serially connecting said groups of conduits, and means for cooling said conduits.

11. Combined ejector-condenser structure comprising an ejector, a condenser into which said ejector discharges the mixture of motive fluid and fluid to be compressed, said condenser comprising a plurality of groups 40 of vertical tubes, chambers at the upper and lower ends of said groups of tubes connecting them in series, and condensate drain pipes connecting a chamber at the upper end of a group of tubes with a chamber at the lower end of said group of tubes.

12. Combined ejector-condenser structure comprising an ejector, a condenser into which said ejector discharges the mixture of motive fluid and fluid to be compressed, 50 said condenser comprising upper and lower chamber, groups of tubes connecting said chambers serially, a drain pipe connecting an upper chamber with a lower chamber, and a liquid seal on the lower end of said drain pipe.

13. Combined ejector-condenser structure comprising an ejector, a condenser, said condenser comprising a group of tubes into which said ejector discharges, a chamber receiving the discharge from said group of tubes, a group of vertically extending tubes 60 receiving fluid from said chamber, a chamber at the upper end of said group of vertically extending tubes receiving fluid there-

from, said tubes projecting a substantial distance above the lower wall of said last named chamber, a drain pipe connecting said last named chamber with said first named chamber, and a liquid seal on the lower end of said drain pipe.

14. Combined ejector-condenser structure comprising an ejector, a condenser receiving discharge from said ejector comprising tube sheets disposed one above the other, condenser tubes disposed between said tube sheets, dams at the upper ends of said tubes, a drainage tube communicating with the space above the upper tube sheet, a long ferrule holding the lower end of said tube in the lower tube sheet, said ferrule having an upwardly extending member spaced therefrom to form a liquid containing space, and means effecting communication between said space and the interior of said ferrule.

15. Combined ejector-condenser structure comprising an ejector, a condenser said condenser comprising upper and lower tube sheets, a plurality of chambers above and below said upper and lower tube sheets, condenser tubes connecting said chambers in series, dam forming ferrules on the upper ends of said tubes, drainage tubes connecting the chambers above said upper tube sheet with the chambers below said lower tube sheet, and means for withdrawing condensate from each of said last named chambers.

16. Combined ejector-condenser structure comprising an ejector, a condenser, said condenser comprising a group of vertically disposed condenser tubes receiving discharge from said ejector and communicating at its lower end with a chamber, a second group of vertically disposed condenser tubes communicating at its lower end with said chamber and at its upper end with a second chamber, a third group of vertically disposed condenser tubes communicating at its upper end with said second chamber and at its lower end with a third chamber, a fourth group of vertically disposed condenser tubes communicating at its lower end with said third chamber and at its upper end with a fourth chamber, dam-forming ferrules on the ends of said groups of tubes communicating with said second and fourth chambers, liquid sealed drainage tubes connecting said second and fourth chambers with said first and third chambers, respectively and liquid sealed condensate discharge pipes communicating with said first and third chambers.

17. Combined ejector-condenser structure comprising an ejector, a condenser receiving discharge therefrom, said condenser comprising a plurality of groups of vertical condenser tubes, a plurality of chambers communicating with the lower ends of said

- tubes, a drainage pipe having branches communicating with each of said chambers, and a liquid seal closing communication between said branches. 65
- 5 18. Combined ejector-condenser structure comprising an ejector, a condenser receiving discharge from said ejector, said condenser comprising a plurality of groups of vertical condenser tubes serially connected, a chamber enclosing said tubes, baffles in said chamber between the several groups of tubes, and means for circulating a cooling medium through said chamber. 70
- 10 19. Combined ejector-condenser structure comprising an ejector, a condenser into which said ejector discharges the mixture of motive fluid and fluid to be compressed, said condenser comprising a plurality of groups of vertical conduits, chambers serially connecting said groups of conduits, and condensate drainage means associated with each of said chambers. 75
- 15 20. Combined ejector-condenser structure comprising an ejector, a condenser into which said ejector discharges the mixture of motive fluid and fluid to be compressed, said condenser comprising a plurality of groups of vertical conduits, chambers at the top and bottom of said groups of conduits connecting them in series, and condensate-sealed condensate drain pipes connecting the chambers at the top of said groups of conduits with the chambers at the bottom of said groups of conduits. 80
- 20 21. Combined ejector-condenser structure comprising an ejector, a condenser into which said ejector discharges the mixture of motive fluid and fluid to be compressed, said condenser comprising a plurality of groups of vertical tubes, chambers at the upper and lower ends of said groups of tubes connecting them in series, and dam-forming ferrules on the upper ends of said tubes. 85
- 25 22. Combined ejector-condenser structure comprising an ejector, a condenser receiving discharge from said ejector comprising tube sheets disposed one above the other, condenser tubes disposed between said tube sheets, dam-forming ferrules on the upper ends of said tubes, and a liquid-sealed condensate drain connecting the space above the upper tube sheet with the space below the lower tube sheet. 90
- 30 23. Combined ejector-condenser structure comprising an ejector, a condenser receiving discharge therefrom comprising a plurality of groups of vertical tubes, chambers at the upper and lower ends of said groups of tubes connecting them in series, liquid-sealed condensate drain pipes connecting said upper chambers with said lower chambers, independent condensate discharge pipes leading from said lower chambers, a pipe into which said discharge pipes deliver, 95
- 35 said pipe ascending to a height causing condensate continuously to stand in said discharge pipes to prevent communication therethrough between said lower chambers. 100
- 40 24. Multi-stage ejector-condenser structure comprising an ejector, a condenser into which said ejector discharges the mixture of motive fluid and fluid to be compressed, said condenser comprising a plurality of groups of vertical tubes, a chamber at the upper end of the first of said groups of tubes receiving the discharge from said ejector, a chamber at the upper end of the last of said groups of tubes receiving the discharge therefrom, and a second ejector receiving the discharge from said second named chamber. 105
- 45 25. Multi-stage ejector-condenser structure comprising ejectors, an interstage condenser comprising a plurality of groups of vertical tubes, chambers at the upper and lower ends of said groups of tubes connecting them in series, one of said upper chambers receiving the discharge from one of said ejectors, and another of said chambers receiving the discharge from said groups of tubes and discharging into another of said ejectors. 110
- 50 26. Multi-stage ejector-condenser structure comprising ejectors, a condenser serially connecting said ejectors, said condenser comprising a plurality of groups of tubes, chambers connecting said groups of tubes in series, and drain conduits connecting the chambers at the opposite ends of at least one of said groups of tubes. 115
- 55 27. Multi-stage ejector-condenser structure comprising ejectors, a condenser serially connecting said ejectors, said condenser comprising a plurality of groups of vertical tubes, chambers connecting said groups of tubes in series, drain conduits connecting said chambers, and means in said conduits allowing passage of fluid in one direction only. 120
- 60 28. Multi-stage ejector-condenser structure comprising ejectors, a condenser serially connecting said ejectors, said condenser comprising chambers disposed one above the other, groups of tubes connecting said chambers in series, dams on the ends of the tubes connecting with the upper chamber, and liquid-sealed conduits connecting said chambers. 125
- 65 29. Multi-stage ejector-condenser structure comprising ejectors, an interstage condenser comprising a plurality of groups of vertical tubes, chambers at the upper and lower ends of said groups of tubes connecting them in series, liquid-sealed drain conduits connecting the chambers at the upper ends of said groups of tubes with the chambers at the lower ends of said groups of tubes, and liquid-sealed drain conduits con-

- necting the chambers at the upper ends of said groups of tubes with the chambers at the lower ends of said groups of tubes, and liquid-sealed conduits discharging condensate from said chambers at the lower ends of said groups of tubes.
30. Multi-stage ejector-condenser structure comprising ejectors, an interstage condenser comprising a plurality of groups of vertical tubes, upper and lower chambers connecting, respectively, the upper and lower ends of adjacent groups of tubes in series, dam-forming ferrules on the upper ends of tubes in upper chambers, drain pipes connecting said upper with said lower chambers, liquid seals on said drain pipes within said lower chambers, and liquid-sealed discharge conduits leading from the bottoms of said lower chambers.
- 20 31. Combined ejector-condenser structure comprising an ejector, a condenser comprising vertical tubes within which fluid discharged by said ejector is condensed, a condensate drain associated with said tubes, and a seal between opposite ends of said tubes effected by condensate in said drain.
- 30 32. Combined ejector-condenser structure comprising an ejector, a condenser comprising a plurality of groups of vertical condenser tubes, a plurality of chambers connecting said groups of tubes in series, condensate drains connecting chambers at the upper ends of said groups of tubes with chambers at the lower ends of said groups of tubes, and means on said drains collecting condensate and forming seals between upper and lower chambers.
- 40 33. Combined ejector-condenser structure comprising an ejector, a condenser comprising a plurality of groups of vertical condenser tubes, a plurality of chambers connecting said groups of tubes in series, condensate drains connecting chambers at the upper ends of said groups of tubes with chambers at the lower ends of said groups of tubes, condensate drainage conduits connected with said lower chambers, and means for holding condensate forming a seal between said lower chambers.
- 50 34. A combined ejector and condenser unit comprising a condenser, said condenser com-

prising a plurality of serially connected groups of vertical conduits, and an ejector mounted upon said condenser and connected to discharge into said conduits. 55

35. A combined ejector and condenser unit comprising a condenser, said condenser comprising a plurality of groups of serially connected vertical tubes, said tubes being of substantially equal length and having their upper ends positioned substantially in the same horizontal plane, and an ejector mounted upon said condenser and connected to discharge into said tubes. 60

36. A combined ejector and condenser unit comprising a condenser, said condenser comprising a plurality of groups of vertical tubes, said tubes being of substantially equal length and having their upper ends positioned substantially in the same horizontal plane, tube sheets supporting the ends of said tubes, and boxes forming a plurality of compartments with each of said tube sheets as a wall thereof, said compartments connecting said groups of tubes serially, and an ejector mounted on one of said boxes and connected to discharge into one of said compartments. 70

37. A combined ejector and condenser unit comprising a condenser, said condenser comprising separated tube sheets, a box forming a plurality of compartments with one of said tube sheets as a wall thereof, and groups of vertical tubes communicating with said compartments, and an ejector mounted on said box and communicating with one of said compartments. 80

38. A multi-stage ejector-condenser unit comprising a condenser, said condenser comprising a plurality of groups of vertical tubes, and chambers connecting said groups of tubes serially, an ejector mounted on said condenser and connected to discharge into one of said chambers, and a second ejector supported upon said condenser and connected to receive fluid from another of said chambers. 90

In testimony whereof I have hereunto affixed my signature this 13th day of August, 1919.

ROBERT SUCZEK.
